DESIGN FOR A STORAGE BATTERY VENT PLUG

Oswald B. Carson, Bronxville, N. Y., assignor to
American Hard Rubber Company, New York,
N. Y.

Application March 9, 1940, Serial No. 90,786

Term of patent 7 years

To all whom it may concern:

Be it known that I, Oswald B. Carson, a citizen
of the United States and a resident of Bronx-
ville, in the county of Westchester and State of
New York, have invented a new, original, and
ornamental Design for a Storage Battery Vent
Plug, of which the following is a specification,
reference being had to the accompanying draw-
ing, forming a part thereof, and in which:

Fig. 1 is a plan view of a storage battery vent
plug showing my new design; Fig. 2 is a side
elevational view thereof.

I claim:

The ornamental design for a storage battery
vent plug, as shown.

OSWALD B. CARSON.
